CATHODE RAY TUBE

Kurt Schlesinger, Berlin, Germany, assignor, by
mesne assignments, to Loewe Radio, Inc., a cor-
poration of New York

Application July 8, 1938, Serial No. 218,165
In Germany August 30, 1937

4 Claims. (Cl. 250—162)

The present invention relates to an improvement of the arrangement according to U. S. patent application Ser. No. 209,323, filed May 21, 1938. In this application a cathode ray tube is described in which a cross-over forming electron-optical system is provided and in which at the point of intersection of the cathode ray a virtual intermediate image of the emissive spot of the cathode is produced between the cathode and the main reproducing lens. At this point of intersection a diaphragm for the purpose of obtaining particularly defined conditions is provided. As by the following electron-optic arrangement the aperture of this diaphragm is projected upon the screen in somewhat reduced size its diameter must not surpass a small multiple of the image point, say .3-.5 mm.

The object of the invention is a special arrangement of the cathode and the adjacent electrodes of a cathode ray tube and particularly of the said diaphragm to ensure that the intermediate image remains unaltered in its position in relation to the main reproducing lens, when the intensity of the cathode ray is controlled.

According to the invention, the opening in the diaphragm is preferably made to be .3-.5 mm. in diameter.

The invention may be more clearly understood by reference to the accompanying drawing. Figs. 1-3 show in a purely diagrammatic fashion and by way of example various kinds of electron-optical systems to be used in a tube according to the invention. In the drawing longitudinal sections through the tubes are shown.

Fig. 1 shows a tube having a cathode 1, the emissive surface of which has a concave shape, a diameter of approximately 2 mm. and a radius of curvature of approximately 1.5 mm., a control grid situated in front of the same, the opening in which grid has a smaller diameter than the hollow cathode, and a first suctional anode 3, which follows on the grid and the diameter of the opening of which, in turn, is smaller than that of the grid. The point of intersection occurring in the path of the rays at 4 has a diameter amounting to approximately .3 mm. It is surrounded by the diaphragm 4'. The diaphragm 4' is raised to the potential of the first anode 3. It is possible by adjusting the radius of curvature of the cathode, or in the case of a given radius of curvature by adjusting the potential of the anode 3 and by simultaneous readjustment of the bias of the grid to remove any variation in size of the image spot on the screen. In the case of the stated diameters of the apertures

and the distances apart as shown in the drawing the critical potential of the suctional anode 3 was approximately 200 volts. The grid bias amounted to between -40 and -10 volts and the slope on an average to 3 mA. over 100 volts.

The point of intersection at 4 is reproduced sharply and without loss on the screen by a main lens 6. A metallic tube 5 separates the lens zone from the preliminary optical system. The perforated plate 7 acts as main anode. A first electron-optical system comprising a diaphragm 8 raised to low potential and a cylindrical electrode 9 has proved to be very useful for obtaining a bright image spot devoid of halo effect. In the embodiment shown the tube cover 8 is connected in direct fashion with the suctional anode 3. The ring 9 is very important for holding back interfering secondary electrons which are always produced at the diaphragm 8. It is shown as being connected in direct fashion with the cathode 1.

In the arrangement according to Fig. 2 the bias at the first anode 3 is considerably greater than in that according to Fig. 1. The cathode 1 is designed as a flat cathode. Owing to the high potential at 3 it is accomplished that the system 2/3 does not exert any refractive effect, so that the direction of the single cathode rays remains un-affected by the grid potential. The possibility of making the cathode surface larger than the area of the aperture in 2 results in the considerable advantage that centering errors of the cathode member have not the least effect. Behind the first anode 3 there is located a first lens comprising a cylinder 12, which is connected for example with the cathode, and the diaphragm 8. The electrode 8 is connected in direct fashion to the tubular member 5. If the lens cylinder 12 has approximately the same potential as the cathode 1, a cross-over point is formed at 4. At this point there is included in the path of the rays the stated perforated diaphragm 4'. As regards potential, this diaphragm is raised to the potential of the first anode 3. In order to avoid secondary emission the diaphragm may consist, at least on its surface, of a substance, such as graphite or hard carbon, which is incapable of performing secondary emission. With an effective cathode surface having a diameter of 1.5 mm. there is obtained with a spacing between 8 and 4 amounting to 10 mm. a diameter of the intersection point of such kind that the same can be enclosed practically without loss by a diaphragm having a diameter of .3-.5 mm.

The reproducing lens following thereon may

correspond to that set forth in Fig. 1. On occasion it has been found convenient, for the purpose of eliminating the halo of the image point caused by secondary emission at the diaphragm 4, to provide a special guard ring of approximately 5 mm. in diameter behind the diaphragm, this ring being connected with a very negative potential, for example with the potential of the cathode. This ring exerts a returning action on the secondary rays deviating at a very large angle from the axis of the beam, and leaves the main rays unaffected.

A further possible embodiment of the invention is illustrated in Fig. 3. The cathode 1 is again a hollow cathode and forms together with the control grid 2 and the anode 3 the control system. There follow a cylindrical ring 9 and a wide-aperture diaphragm 8. The cylinder 9 reflects the stray electrons. The diaphragm 8 together with the tubular member 5, which is raised to a higher potential, build up, in the manner already indicated in the above, a first electron lens. The main lens of the tube is constituted by the upper edge of the tubular member 5 and element 5a in conjunction with the anode diaphragm 1.

It has been found that it is possible to obtain on the screen a constant diameter of the image point, when the radius of curvature of the emissive surface of the cathode is equal to approximately the distance of the centre of the cathode from the anode 3. Then all rays from the large-surface cathode converge to a point of intersection 4.

An arrangement of this kind is described in the copending U. S. patent application Ser. No. 212,316, filed June 7, 1938.

The cross-over 4 produced by means of elements 1, 2, 3, is again used as the object of the electron-optical reproduction on the screen and is, according to the present invention, enclosed by the diaphragm 4'. The lens 5a/1 reproduces this point of intersection on the screen 20.

Special means are provided for eliminating the loss of contrast due to a general illumination of the screen initially occurring upon this reproduction. For this purpose there is provided the above mentioned first lens arranged in close proximity to the point of intersection. The equi-potential surfaces indicated in broken lines result upon the reciprocal of the field of the tubular member 5.

Special means are provided for eliminating the loss of contrast due to a general illumination of the screen initially occurring upon this reproduction. For this purpose there is provided the above mentioned first lens. The equi-potential surfaces indicated in broken lines result upon the reciprocal of the field of the tubular member 5, which is raised to approximately one-third of the anode potential, by reason of the intermediate diaphragm 8, which by means of a potentiometer 24 is adjusted to a lower potential than the tubular member. If the bias of the intermediate diaphragm 8 is suitably adjusted at 14, a refractive plane is built up between the point of intersection and 8.

The diaphragm 8 and 3 can also be provided in fixed connection, and the bias of 5 adjusted alone, from the exterior, at a potentiometer 21. For this purpose 5 and 5a are separated, as the potential at 5a has already been pre-determined by adjustment of the sharpness of the image point on the screen.

75. I claim:

1. In a cathode ray tube comprising a target element, an indirectly heated large surface cathode, a first anode diaphragm, and a control electrode having the shape of a diaphragm and being arranged between said cathode and said first anode diaphragm: a cross-over forming electron optical system including said cathode, said control diaphragm, said first anode diaphragm and a further diaphragm arranged adjacent to said first anode diaphragm on its side facing said screen and closely surrounding said cross-over, the spacing between said first anode diaphragm and said further diaphragm being approximately equal to the spacing between said first anode diaphragm and said control diaphragm; an electron-optical lens system for producing an image of said cross-over on said target element; and means for deflecting said cathode ray to scan said target element.

2. In a cathode ray tube comprising a target element, an indirectly heated large surface cathode, a first anode diaphragm, and a control electrode having the shape of a diaphragm and being arranged between said cathode and said first anode diaphragm: a cross-over forming electron optical system including said cathode, said control diaphragm, said first anode diaphragm and a further diaphragm arranged adjacent to said first anode diaphragm on its side facing said screen and closely surrounding said cross-over, the spacing between said first anode diaphragm and said further diaphragm being approximately equal to the spacing between said first anode diaphragm and said control diaphragm; an electron-optical lens system comprising a cylindrical electrode and a second anode diaphragm for producing an image of said cross-over on said target element, said cylindrical electrode and said second anode diaphragm being mounted in axial consecution adjacent to said further diaphragm on its side facing said target element, said cylindrical electrode being electrically insulated within the tube from said further diaphragm and from said second anode diaphragm; and means for deflecting said cathode ray to scan said target element.

3. In a cathode ray tube comprising a target element, an indirectly heated large surface cathode, a first anode diaphragm, and a control electrode having the shape of a diaphragm and being arranged between said cathode and said first anode diaphragm: a first electron-optical system including said cathode, said control diaphragm and said first anode and adapted to parallel the cathode ray after emergence from said cathode; a cross-over forming electron-optical system mounted adjacent to said first anode on its side facing said target element and including, in axial consecution, a cylindrical electrode, a second anode diaphragm, and a further diaphragm closely surrounding said cross-over, said cylindrical electrode being electrically insulated within the tube from said first anode diaphragm and from said second anode diaphragm; a further electron-optical system for producing an image of said cross-over on said target element; and means for deflecting said cathode ray to scan said target element.

4. In a cathode ray tube comprising a target element, an indirectly heated large surface cathode, a first anode diaphragm, and a control electrode having the shape of a diaphragm and being arranged between said cathode and said first anode diaphragm: a first electron-optical system including said cathode, said control dia-

phragm and said first anode and adopted to parallel the cathode ray after emergence from said cathode; a cross-over forming electron-optical system mounted adjacent to said first anode on its side facing said screen and including, in axial consecution, a cylindrical electrode, a second anode diaphragm, and a further diaphragm closely surrounding said cross-over, said cylindrical electrode being electrically insulated with-

in the tube from said first anode diaphragm and from said second anode diaphragm, said further diaphragm being connected to said first anode; a further electron-optical system for producing an image of said cross-over on said target element; and means for deflecting said cathode ray to scan said target element. 5
